EQUALIZING VALVE ARRANGEMENT FOR
PACKERS

Harry B. Ziegler, Odessa, Tex., assignor to Halliburton Oil Well Cementing Company, Duncan, Okla.

Application June 7, 1938, Serial No. 212,265

4 Claims. (Cl. 166—1)

This invention relates to oil well equipment and more particularly to an equalizing valve arrangement adapted for use with packers designed to be set and subsequently released in a well.

5 Packers are often placed in an oil well to seal a conduit to a casing or the wall of the well. One common use for a packer is in connection with a testing tool such as is shown in the U. S. patent to Simmons, No. 1,930,987. It is often 10 difficult once the packer has been seated to remove the same from the well, due to the difference in liquid pressure which may exist above and below it or inside and outside of the conduit to which it is connected. To overcome this difficulty it is common practice to employ what is 15 called an equalizing valve. An example of an equalizing valve suitable for this purpose is disclosed in the patent to Dower, No. 249,228, granted November 8, 1881, for "Oil well packer." 20 When an equalizing valve of the type shown by the Dower patent mentioned is employed and the tubing or other conduit means which carries the packer is lifted the pressure above and below the packer is equalized and the only strain to which 25 the tubing is subjected is that due to the resistance of the packer to being unseated.

It is common experience to find, however, that the packer has been firmly stuck in the well and cannot be released by merely pulling thereon with 30 all the stress which the tubing is capable of standing. This occurs especially in connection with rat hole packers of the type shown in the patent to Simmons mentioned above, but is also likely to happen with other types of packers as well. 35 When such a condition arises it is desirable to assist the tubing to release the packer by exerting fluid pressure as by means of a pump in the space beneath the packer, thus tending to lift the same. Where an equalizing valve of the type shown by Dower is employed this is impossible 40 because any fluid forced down through the tubing flows outwardly through the equalizing valve and does not exert any pressure differential below and above the packer.

45 It has already been proposed to overcome this last mentioned difficulty by providing an equalizing valve arrangement which opens and then closes practically immediately, thereby permitting the pressure above and below the packer to equalize for a fraction of a second and still permit fluid pressure to be exerted below the packer. Such an equalizing valve arrangement is disclosed in the patent to Dean Hanes, No. 2,144,842, granted January 24, 1939, for "By-pass assembly 50 for packers."

In accordance with the present invention it is proposed to provide an equalizing valve assembly which is similar in some respects to the Dower equalizing valve and the Hanes equalizing valve but which is superior thereto in that not only is 5 the pressure permitted to equalize when the tubing is subjected to lifting strain but which will also enable pump pressure to be exerted beneath the packer to assist the tubing in lifting the same and which at the same time permits fluid to flow 10 from above the packer to a point beneath the same for more than an instant of time and whenever the pressure above the packer is greater by a pre-determined amount than that below the same while the tubing and packer are being 15 pulled upwardly.

Accordingly, it is one object of the invention to devise an equalizing valve for packers which has certain advantages in operation and which will enable a packer to be more easily removed 20 from a well.

It is a further object of the invention to provide a novel equalizing and pump out valve assembly for use in connection with a packer for an 25 oil well.

Other objects and advantages reside in certain novel features of the arrangement and construction of parts, as will be more apparent from the following description taken in connection with the accompanying drawing, in which:

30 Figure 1 is a vertical cross-sectional view of an equalizing valve assembly constructed in accordance with the principles of the invention and illustrating the parts in the position which they occupy when a packer connected to the lower end 35 thereof is being seated; and

Figure 2 is a vertical cross-sectional view of the same arrangement shown in Figure 1 but illustrating the position of the parts when the tubing is subjected to a strain tending to lift 40 the packer.

45 Referring to the drawing in detail, it will be seen that the equalizing valve assembly there shown includes two telescoping members, the inner one of which is designated 11 and is sometimes referred to as a mandrel. The outer telescoping member is preferably made of two parts designated 12 and 13, the lower part 12 being provided with a stud 14 threaded both inside and outside so as to provide means for connection to a mandrel and upper shoe of a rat hole packer, it being understood that the mandrel of the packer would be threaded into the interior of the stud while the shoe is threaded on the outside thereof.

The parts 12 and 13 of the outer telescoping 55

member are screw threaded together by means of the threads 15. Means is further provided in the part 13 for preventing relative movement between the two telescoping members, the arrangement illustrated including a dowel pin 16 adapted to cooperate with a slot 17 in the inner telescoping member. Any kind of a spline connection could be used in place of the pin and slot arrangement illustrated for preventing relative movement between the two telescoping members.

10 Two valves are associated with and operated by the telescoping members just described. One is commonly referred to as an equalizing valve and consists of a valve body 18 formed at the upper end of the part 13 of the outer telescoping member, this valve body being adapted to cooperate with a valve seat 19 provided in a coupling member 20 screw threaded to and integral with the inner telescoping member 11. The member 20 is provided with a screw threaded extension at its upper end to provide means for connecting the whole assembly to drill pipe or tubing. At its lower end the coupling member 20 may be provided with a perforated sleeve 21 which, if used, will prevent cuttings or pieces of rock from entering the valve assembly and interfering with its proper operation.

15 The second valve associated with and operated by the telescoping members may be referred to as a pump out valve. It consists of a valve body 22 integral with the lower end of the inner telescoping member 11. This valve body is adapted to engage a valve seat 23 provided on the lower end of the part 13 of the outer telescoping member.

20 It will be seen that the equalizing valve and the pump out valve just described are both operated by relative movement between the telescoping member, the equalizing valve being closed when the members are fully telescoped together while the pump out valve is open at this time and the pump out valve being closed and the equalizing valve opened when the telescoping members are pulled apart or extended as far as they will go.

25 It will also be seen that the equalizing valve and the pump out valve constitute means for moving the outer telescoping member either to set or release the packer. When the drill pipe is set down the member 20 engages the top of the part 13 and pushes downwardly thereon. Similarly, when the drill pipe is raised and tension taken therein, the pump out valve seats and acts as a means for lifting the part 13, the lifting force being transmitted through the pump out valve.

30 It will be seen from the drawing that either the equalizing valve or the pump out valve is closed at all times except when the telescoping members are being moved one relative to the other.

35 The equalization of pressure normally takes place by transmission from the exterior of the outer telescoping member through the equalizing valve when the telescoping members are extended and thence to the interior of the inner telescoping member 11 through a hole or port 24 therein. As shown in the drawing the inner telescoping member 11 is provided with a central passageway 25 into which the hole or port 24 opens. The lower end of this passageway is closed by means of a one-way or check valve consisting of a valve body 26 adapted to seat, under the influence of a spring 27 against the valve seat member 28 screw threaded to the lower end of the inner telescoping member 11.

40 The inner telescoping member 11 is also pro-

vided with a longitudinally extending bore 29 which acts as a choke but which is open at all times for the passage of fluid between the drill pipe or tubing connected to the upper end of the assembly by means of the coupling member 20 and the mandrel of the packer connected to the interior of the stud 14 at the lower end of the assembly. The bore 29 may pass straight through from one end to the other of the telescoping member 11 but it is preferable to make this member of several pieces and join them together in which case the bore need not necessarily be straight and may be as illustrated in the drawing. In one form of the invention (and this is the form illustrated) the inner telescoping member 15 11 is made of one piece, the bore 29 being formed by cutting a longitudinal slot therein and then welding a curved cover plate thereover.

45 From the above description, it will be apparent that the equalizing valve assembly may be operated as follows: With drill pipe or tubing connected to the upper end thereof and with a packer connected to the lower end, the apparatus is lowered into a well. If the packer is of the rat hole type as soon as it rests upon the rat hole shoulder the parts will assume the position shown in Figure 1 and the packer may be firmly seated due to the weight of the drill pipe or tubing being transmitted to the packer through the assembly, this pressure being transmitted through 30 the parts 18 and 19 of the equalizing valve as described above. If the assembly is used in connection with a formation tester, the tester valve may then be opened and fluid conducted from a point beneath the packer upwardly through the 35 choke bore 29 of the equalizing valve assembly and into the drill pipe above the formation tester, it being understood that in such case the tester valve will be above the equalizing valve assembly shown in the drawing. The tester valve may 40 then be closed and a sample from the formation entrapped thereabove. The operator may then proceed to release the packer from its seat. The drill pipe or tubing is first raised and strain taken therein to attempt to pull the packer off of its 45 seat. The parts then take the relative position shown in Figure 2, the equalizing valve opening and the pump out valve closing. Since the equalizing valve is opened, pressure may be transmitted through or under the perforated sleeve 21 50 in through the port 24 and downwardly through the inner bore 25 of the inner telescoping member 11, and to a point beneath the packer through the valve 26, this valve opening (as shown in dotted line in Figure 2) whenever the pressure 55 within the bore 25 is greater than that beneath the valve 26 by an amount sufficient to overcome the effect of the spring 27.

55 Assuming now, however, that even after the pressure above and below the packer has been 60 equalized, the operator is still unable to remove the packer from the well, fluid pressure may be exerted beneath the packer. It will be understood that unless the well has been flowing through the drill pipe or tubing this is only an 65 emergency measure where the equalizing valve and packer are used in connection with a formation tester and that the entrapped sample above the tester valve will be lost or contaminated if it becomes necessary to exert pump pressure as 70 an aid to releasing the packer.

65 In exerting pump pressure the operator will open the tester valve and force fluid under pressure downwardly into the well, pressure of this fluid being transmitted through the choke bore 75

29 to a point beneath the packer. As soon as the pressure beneath the valve 26 is greater than that within the bore 25 of the inner telescoping member 11, the valve 26 will close. For this reason, no fluid can be transmitted from the drill pipe to the exterior of the telescoping members except around the bottom of the packer, even though the drill pipe or tubing is subjected to a lifting force or strain at all times. Should the 10 operator cease pumping and attempt to spud or move the apparatus up and down to aid in releasing the packer, the valve 26 will open whenever the pressure above the packer is greater than that below it, and will close whenever the 15 pressure beneath the packer is greater than that above it. The action is thus such as to materially aid in releasing the packer.

While only one embodiment of the invention has been shown and described herein, it is obvious that various changes may be made in the arrangement and construction of parts without departing from the spirit of the invention or the scope of the annexed claims.

I claim:

25 1. An arrangement adapted for use in connection with a packer for oil wells or the like comprising an inner conduit member and an outer conduit member telescoped together, said members having a valve arrangement associated therewith for controlling the flow of fluid around or through the telescoped portions of said members, said arrangement including an equalizing valve operated by relative movement between said members and adapted to close when said members are fully telescoped and open when said members are extended, a pump out valve also operated by relative movement between said members and adapted to close when said members are extended and open when said members 40 are fully telescoped, said members having a passageway therein for conveying fluid from the exterior to the interior of said members when the same are extended to open the equalizing valve and close the pump out valve and a check valve 45 in said passageway for limiting the flow of fluid therein in the direction aforesaid.

2. An equalizing valve assembly for use in connection with a packer for oil wells or the like,

said assembly including conduit members telescoped together and serving as means for connecting tubing or drill pipe to the packer, said conduit members having an equalizing valve, a pump out valve and a check valve associated therewith for controlling flow of fluid around or through the telescoped portions thereof, means associated with said equalizing valve to conduct fluid from the exterior to the interior of said conduit members when said equalizing valve is open, said equalizing valve and said pump out valve being operated by relative movement between said members and said check valve providing means for limiting the flow of fluid through said equalizing valve and said conducting means from the exterior to the interior of said members when said equalizing valve is open and said pump out valve is closed.

3. An equalizing valve assembly for use in connection with a packer for oil wells or the like including two conduit members telescopically connected together, means for preventing fluid from flowing from the exterior to the interior of said members when said members are fully telescoped together, means for conducting fluid from the exterior to the interior of said members when the members are in extended position, said fluid conducting means having a check valve therein for preventing fluid from flowing therethrough from the interior to the exterior of said members.

4. An equalizing valve assembly for use in connection with a packer for oil wells or the like, said assembly including a centrally disposed mandrel having an open passageway therethrough and having connecting means at its upper end, a member telescoped upon said mandrel and having connecting means at its lower end, conduit means for conducting fluid from the exterior to the interior of said assembly, a valve operable by relative movement between said mandrel and said member for opening or closing said conduit means and a check valve in said conduit means for preventing fluid flowing therethrough except from the exterior to the interior of said assembly.

HARRY B. ZIEGLER.
